mington, Del., a corporation of Delaware

Application May 4, 1942, Serial No. 441,633

4 Claims. (Cl. 101—227)

This invention relates to printing machines and particularly to devices for controlling the feeding of a web to be printed to such machines.

In printing machines of the character to which the present invention pertains a continuous web is passed through the machine to have spaced impressions made thereon by the printing means in the machine and thereafter the web is severed into sheets each of which bears such an impression. It is desirable that the various impressions made on the web be uniformly spaced, and it is also desirable, where a web severing means is incorporated in the machine, that such means shall accurately divide the web into sheets of uniform size intermediate the impression and yet have uniform and predetermined margins adjacent the printed matter on the sheets. All this entails accurate control of the feeding of the web to the printing machine and to enable this to be accomplished in a novel and expeditious manner is a primary object of this invention.

The present invention is particularly adapted for use with a printing machine embodying a rotary printing couple including an arcuate rotary printing medium, such as a plate, blanket or type segment, that cooperates with a rotary platen or impression cylinder to print upon the web. As the web advances through the printing couple it receives an impression from the printing medium during each rotation of the couple and at least one element of the printing couple embodies an interrupted surface so that there are periods during the rotation of the couple in which the web is not gripped thereby, and during these periods the web comes to rest thereby enabling the web severing means to divide the web into separate sheets.

Heretofore it has been proposed to employ web feeding means comprising intermittently driven feed rollers to advance a web through the printing couple of a printing machine in a step-by-step manner so as to enable printing to be effected on the web during the periods of advancing movement and severance of the web during the time the web is at rest in the course of such advancing movement. In such prior arrangements it has been customary to locate such a web feeding means beyond the printing couple in the direction of travel of the web, usually intermediate the printing couple and the severing means. While this has been useful in accurately gauging the size of the sheets severed from the web, it has not afforded a reliable control of the registration of the sheet sections of the web with the printing medium on the printing couple, with the result

that often the printed matter was not properly located on the sheets. This was chiefly caused by the tendency of the web to buckle or creep due to the intermittent driving action of the printing couple upon it. Moreover, the feed rollers acting upon the printed portion of the web tended to smear the ink thereon, unless such means were positioned a considerable distance away from the printing couple to enable the ink to dry thoroughly before coming in contact with the web driving rollers.

It is therefore another important object of the present invention to insure accurate registration of the web with the printing medium by arranging the automatic web feeding and stopping means to be effective upon the web prior to advance thereof into the printing couple to thereby effectively prevent any objectionable movement of the web and yet enable the web feeding and stopping means to be located closely adjacent the printing couple.

A further object is to arrange the web feed rollers and a braking means therefor to be operated in positive timed relation with the operation of the printing means.

A still further object is to render the apparatus adjustable to thereby enable production of sheets of varying width.

Still another object is to provide web feeding, stopping and severing means of simple and economical construction which may be readily attached to conventional printing machines that are ordinarily equipped to handle only pre-cut sheets or forms, to thereby adapt such machines to the handling of web material.

Other and further objects of the present invention will be apparent from the following description and claims and are illustrated in the accompanying drawings which, by way of illustration, show a preferred embodiment and the principle thereof and what I now consider to be the best mode in which I have contemplated applying that principle. Other embodiments of the invention embodying the same or equivalent principle may be used and structural changes may be made as desired by those skilled in the art without departing from the present invention and the purview of the appended claims.

In the drawings,
50 Fig. 1 is a side elevational view of a printing machine embodying my invention;
Fig. 2 is a plan view of the printing machine;
Fig. 3 is a vertical sectional view of the web feeding and stopping means and a portion of the printing machine proper;

Fig. 4 is an elevational detail view of certain control mechanisms for the web feeding and stopping means;

Fig. 5 is a fragmental plan view of the mechanisms shown in Fig. 4;

Fig. 6 is a fragmental vertical sectional view taken on the line 6—6 on Fig. 5;

Fig. 7 is a fragmental plan sectional view taken on the line 7—7 on Fig. 6;

Fig. 8 is an enlarged plan view of the web severing means and associated structure;

Fig. 9 is a vertical sectional view taken on the line 9—9 on Fig. 8;

Fig. 10 is a cross sectional view taken on the line 10—10 on Fig. 9; and

Fig. 11 is a plan sectional view taken on the line 11—11 on Fig. 10.

In the accompanying drawings I have illustrated my novel invention in association with a printing machine A, Figs. 1 and 2. The web handling mechanism B, comprising web supply means and web feeding and stopping means, is disposed on one side of the printing machine A, and the web severing and sheet delivery mechanism C is located on the other side of this machine. The printing machine A is preferably of conventional design and the mechanisms B and C are arranged to be attached to such a printing machine so as to adapt it for use with a web W. These mechanisms are desirably readily detachable from the printing machine so that they may be removed when it is desired to utilize the printing machine independently of them as, for example, where the machine is to be employed for printing pre-cut sheets or the like.

The printing machine A in the present instance is an offset lithographic press provided with a blanket cylinder 15, Fig. 3, carrying a printing surface or blanket 17 which receives inked impressions from a planographic plate 18 carried by a plate cylinder 19. The blanket 17 cooperates with a platen cylinder 16 to print upon a web W which is passed into the bite of the cylinders 15 and 16. The opposed surfaces of the blanket 17 and the impression face of the platen cylinder 16 are interrupted circumferentially so that the web W is periodically released from the bite of the printing couple, and during these periods the web is brought to rest to enable a section thereof bearing an impression to be severed from the web by the severing mechanism C, Figs. 1 and 2, whereby the web is divided into separate sheets. The web handling mechanism B is so arranged as to accurately time the stoppage and resumption of movement of the web so that the printed matter will be accurately positioned on the sheets and also to insure that the sheets will be of uniform size.

The web handling mechanism B is supported by a stand or frame carried by a base structure 25, Fig. 3, that is preferably mounted on casters 26 so as to facilitate moving the web handling mechanism B into or out of association with the printing machine A. When the web handling mechanism B is to be operatively associated with the printing machine A, the base 25 is connected by turnbuckles 27 to a tie rod 28 on the frame 29 of the printing machine A. The web W is withdrawn from a roll R of paper or other material supported on a shaft 30 journaled in bifurcations in the ends of arms 31, the other ends of these arms 31 being pivotally mounted on a tie rod 32 extending across the base 25. Vertical links 33 extend upwardly from the arms 31 and

are pivotally connected at their upper ends to rocker arms 34 secured to a rock shaft 35, Figs. 2 and 3, which is journaled in uprights 36 included in the frame of the web handling mechanism B. The upper ends of the links 33 are offset at right angles to clear the shaft 35, as shown in Fig. 3, and the arrangement is such that when the arms 34 are positioned past dead center, the weight of the roll R acting through the links 33 urges the arms 34 against stops 37 carried by the frame of the mechanism B. The arms 31 and the roll R carried thereby are thus normally maintained in raised position, but when it is desired to lower the arms 31, for instance when a new roll is to be inserted, the shaft 35 is turned by means of a crank 38, Figs. 1 and 2, to swing the arms 34 to the other side of dead center, enabling the arms 31 to descend so that a new roll may be conveniently introduced. The crank 38 is then turned to raise the arms 31 and roll R clear of the floor or other surface on which the machine rests.

There are, in the present instance, two different devices embodied in the mechanism B for feeding the web W from the roll R to the printing machine A. One of these, described more fully hereinafter, effects the accurately timed intermittent advancing and stopping of the web which is necessary to the successful operation of the entire apparatus. However, inasmuch as a roll of paper R, particularly when new, is quite heavy and may possess considerable inertia, it is preferred not to rely upon the just referred to web advancing means for effecting the initial withdrawal of the web W from the roll R, since the load which this would place upon the aforesaid device might be detrimental to the accuracy with which it should function. Therefore, I have provided suitable means for effecting the initial withdrawal of the web W from the roll R.

The last referred to means comprises an electrically-operated motor unit 40, Figs. 1, 2 and 3, pivotally mounted on a horizontal shaft 41 secured to the frame of the mechanism B, this motor unit 40 being provided with friction rollers 42 which rest on the upper periphery of the roll R. When the motor in the unit 40 is in operation, the rollers 42 impart unwinding movement to the roll R to effect withdrawal of a web W from this roll.

From the roll R the web W passes beneath a diabolo 45 which is carried by a rocker 46 pivotally mounted on the uprights 36. The rocker 46 is provided with short lever arms 47 which are connected by springs 48 to plates 49 secured to the uprights 36 in spaced relation to the pivot centers of the rocker 46. Spaced holes are provided in the plates 49 and by anchoring corresponding ends of the springs 48 in selected of these holes the tension of these springs may be adjusted to enable the diabolo to impart the desired tension to the web W. After passing the diabolo 45, a web W is led upwardly to the top of the frame of the web handling mechanism B and is passed around a roller 50, Figs. 2 and 3, mounted on a shaft 53 carried by uprights 51 forming part of the frame of the mechanism B, the edges of the web being guided by collars 52 on the roller 50.

It has been mentioned hereinabove that the web handling mechanism B is provided with a motor unit 40 for effecting withdrawal of the web W from the roll R and with additional means for accurately feeding the web in a step-by-step

manner into the printing machine A. The latter means comprises the web feeding and stopping unit, generally designated 55, Figs. 1, 2 and 3, which is carried between side plates 56 and 57 on the frame of the web handling mechanism B. The side plates 56 and 57, Figs. 2, 3 and 6, are interconnected by a cross bar 58 which is connected by threaded studs 59 to a portion of the frame 29 of the printing machine A.

The web W, after passing over the roller 50, 10 advances through a web looping means to be described presently and into cooperative relation with the devices included in this web feeding and stopping unit 55. Since the motor unit 40 is to operate in such a manner that the proper amount of web is withdrawn to be available for advancement into the printing machine A each time the unit 55 functions to impart movement to the web, I have provided means controlled by the just-mentioned web looping means for automatically regulating the operation of the motor unit 40.

The web looping means comprises a roller 60 which is fixedly mounted on a horizontal shaft 61, the ends of which extend through vertical 23 guide slots 62 in the uprights 51. The roller 60 is effective to form a loop in the web W intermediate the roller 50 and the web feeding and stopping unit 55, thereby taking up any slack in this portion of the web. As the unit 55 operates to feed the web into the printing machine A, in the manner presently to be described, the loop in the web W is reduced in size and the roller 60 rises. As shown in Figs. 5 and 6, pinions 63 secured to the shaft 61 mesh with vertically extending racks 64 positioned on the uprights 51 adjacent the slots 62, and this serves to maintain the shaft 61 in a horizontal position as it moves vertically.

As the roller 60 nears the upper limits of the guide slots 62, toward the completion of each step of advancing movement to the web W by the unit 55, the shaft 61 engages an arm of a lever 65, Fig. 3, pivotally mounted at 66 on one of the uprights 51, and as the shaft 61 continues to rise it rocks the lever 65 slightly to effect closure of a normally open switch 67 which is included in the electrical circuit of the motor of the unit 40. Such closure of the switch 67 completes this circuit and sets the motor unit 40 in operation, thereby imparting unwinding movement to the roll R. As the roll unwinds, the web looping roller 60 takes up the slack in the web W withdrawn from the roll R, the roller 60 descending as it does so until a loop of predetermined size is formed in the web W, whereupon the switch 67 opens and interrupts operation of the motor 40. A brake 68, Fig. 1, on the shaft 30 of the roll R maintains sufficient friction on this shaft at all times to prevent the roll R from overrunning when the motor unit 40 ceases operation. Thus it is insured that the right amount of slack in the web W will be available each time the web feeding unit 55 is ready for operation, and consequently the unit 55 merely need overcome the relatively light load of the roller 60 rather than the relatively heavy load which would be imposed upon it if it operated to withdraw the web W directly from the roll R.

After the web W passes from the looping roller 60 it is led over a guide roller 70, Figs. 2, 3 and 6, rotatably mounted on a stationary shaft 71 carried by the side plates 56 and 57, this roller 70 being provided with collars 72 for guiding the edges of the web W. The web W is then passed 75

successively around a clamping roller 73 and a feed roller 74, the web assuming an S-shaped bend as it passes around the rollers 73 and 74. Preferably, the feed roller 74 is discontinuous, 5 as shown in Fig. 2, comprising a central knurled portion and a series of discs on either side thereof, all of which are secured to a shaft 75 journaled in the side plates 56 and 57. The clamping roller 73 is rotatably mounted on a shaft 76 carried by a rocker 77 pivotally mounted on a shaft 78 journaled in the side plates 56 and 57 of the web feeding unit 55. Springs 79 anchored to a rod 80 extending between the side plates 56 and 57 are connected to threaded rods 81, Fig. 6, carrying wing nuts 82 which bear against the rocker 77, causing the clamping roller 73 to be urged against the feed roller 74. The tension of the springs 79 may be adjusted by turning the wing nuts 82 until the desired contact pressure between the rollers 73 and 74 is attained.

The feed roller 74 is adapted to be intermittently driven in such relation to the printing couple 15-16, Fig. 3, that the amount of web 23 which is advanced through this printing couple each time the web feeding unit 55 operates is slightly greater, by a predetermined extent, than the effective length of the opposed impression surfaces of the blanket 17 and platen 16. Referring to Figs. 3 and 4, a shaft 85 in the printing machine A is arranged to be driven by a suitable source of power, such as the motor 86 of the printing machine, in timed relation with the rotation of the cylinders 15 and 16 of the printing couple. A gear 86 is secured to this shaft outwardly of one of the side plates of the printing couple, and this gear is adapted to mesh with a gear 87, Figs. 4, 5 and 7, of the same diameter as the gear 86, the gear 87 being rotatable 30 mounted on a sleeve 88, Fig. 7, on the shaft 78 in the web feeding unit 55, outwardly of the side plate 56 of this unit. A pawl 90, Fig. 4, pivotally secured to the outer face of the gear 87 is normally urged by a spring 91 into engagement with the periphery of a ratchet wheel 92 mounted on a reduced portion of the sleeve 88, Fig. 7, outwardly of the gear 87. A gear 93, 35 Figs. 5 and 7, of the same diameter as the gear 87 is rotatably mounted on a reduced portion of the sleeve 88 inwardly of the gear 87. The sleeve 88 is pinned to the shaft 78 and is connected to the gear 93 and the ratchet wheel 92 by pins 94 which extend parallel to the shaft 78 through the shouldered portion of the sleeve 88, on which 40 the gear 87 is rotatably mounted, and into sockets in the gear 93 and ratchet wheel 92, thereby securing said gear and ratchet wheel to the shaft 78.

When the web handling mechanism B is assembled in operative relation to the printing machine A, as shown in Fig. 1, the gears 86 and 87 are meshed and the gear 87 is constantly driven by the gear 86 so long as the printing machine is in operation. The pawl 90, Fig. 4, carried by the gear 87 affords a connection between this gear and the ratchet wheel 92 secured to the shaft 78, for thereby driving the shaft 78 rotatably in a counter-clockwise direction, as viewed in Fig. 4. The gear 93, Figs. 5 and 7, secured to the shaft 78 meshes with a pinion 95 fast to the shaft 75 of the feed roller 74 so that the feed roller 74 is driven clockwise, as viewed in Fig. 4, to advance the web W into the bite of the printing couple 15-16, Fig. 3, so long as the gear 93 is rotating. The circuitous path of the web W

around the clamping roller 73 and feed roller 74, Fig. 6, insures sufficient friction to prevent slippage of the web relative to the feed roller. Prior to entering the bite of the printing couple 15-16, Fig. 3, the web W passes beneath an adjustable guide member 86 included in the printing machine A, this member serving to guide the web into the printing couple substantially at a tangent to the cooperating cylinders 15-16.

Means are included in the web feeding and stopping unit 55 for periodically interrupting the advancing movement of the web W, and in the present instance such means include an adjustable cam generally designated 100, Figs. 4 and 5, positioned coaxially of the ratchet wheel 92 and adapted to cooperate with a roller 101 on the pawl 90 for intermittently pivoting the pawl 90 out of engagement with the teeth of the ratchet wheel 92 for a selected portion of each cycle of rotation of the gear 87. The cam 100 comprises a stationary plate 102 and an adjustable plate 103, these plates being mounted on the shaft 78 but not secured thereto and having cam surfaces concentric with respect to the shaft 78 and of equal radii greater than the radius of the ratchet wheel 92. A strap 104 secured to the stationary cam plate 102 is fastened to the end of the stationary shaft 71 on which the guide roller 70 is mounted, thereby securing the plate 102 against rotation. A threaded stud 105, Figs. 4 and 7, projecting from the face of the cam plate 102 is received in an arcuate slot 106 formed in the adjustable cam plate 103, and a nut 107 is provided on the stud 105 to clamp the cam plate 103 to the cam plate 102 in the desired relative positions thereof.

As the pawl 90 moves into cooperative relation with the cam 100, the roller 101 rides up on the cam surface and the pawl 90 is disengaged from the ratchet wheel 92. This is timed to occur shortly after the web is released from the grip of the printing couple 15-16, Fig. 3, as the interrupted impression surfaces of the blanket 17 and platen 16 move out of web engaging relation. The web thereupon comes to rest and remains stationary while the roller 101, Fig. 4, is riding on the cam 100. As the roller 101 rides off this cam, the pawl 90 again engages the periphery of the ratchet wheel 92 and web feeding is resumed. This occurs shortly prior to the instant the printing couple again grips the web. In this manner the printed impressions on the web W are accurately spaced apart to leave a predetermined margin adjacent each impression when the web is later severed into sheets.

It is desirable that movement of the web W be arrested when the pawl 90 is disengaged from the ratchet 92 in order that the area of the web which is to receive an impression from the printing couple will be accurately registered with the printing medium carried by this couple. This would be defeated if any unwanted movement were to be imparted to the web due, for instance, to the momentum of the intermittently driven parts of the web feeding unit 55, or as a result of the tendency of the web looping roller 60 to retract the web. For this reason I employ a brake mechanism which is automatically operated, whenever the pawl 90 is disengaged from the ratchet, to frictionally restrain movement of the feed roller 74 and therefore the web W.

Referring to Figs. 5, 6 and 7, a brake drum 110 is secured to the shaft 78 inwardly of the side plate 56. A brake band 111 encircling the drum 110 carries at each end thereof a lug 112. A rod

113 extends vertically through openings in the lugs 112 and is supported by a bracket 114 secured to the inner face of the side plate 56. A coiled compression spring 115 surrounding the rod 113 is disposed between the lugs 112 and tends to maintain these lugs separated sufficiently so that normally no appreciable braking force is applied to the drum 110 and shaft 78 by the brake band 111. The lower lug 112 is seated on a shoulder on the rod 113, and the upper lug 112 is connected to and supports a collar 116 which is provided with a V-shaped notch receiving a tooth 117 formed on a collar 118 disposed above the collar 116 on the rod 113, the collar 118 being restrained against upward movement by lock nuts 119 threaded on the rod 113. An arm 120, Fig. 5, extending from the collar 118 is pivotally connected by a link 121 to an upwardly extending arm 122, Figs. 6 and 7, secured to a rock shaft 123 journaled in the side plate 56. A downwardly extending arm 124 secured to the rock shaft 123 is normally urged by a spring 125 against a stop pin 126 to normally maintain the tooth 117 of the collar 118 seated in the notch in the collar 116 on the vertical rod 113.

The rock shaft 123 extends through the side plate 56 and carries an arm 130, Fig. 4, on the end of which a roller 131 is mounted. This roller is disposed in the path of a cam plate 132, Figs. 3, 4, 5 and 7, secured to the inner face of the gear 87. The cam plate 132 is disposed to engage the roller 131 substantially concurrently with the engagement of the roller 101 on the pawl 90 with the cam 100, and thereupon the cam plate 132 rocks the arm 130 and shaft 123, rocking the lever 122, Fig. 6. The lever 122 pulls the link 121 and thereby rocks the collar 118 sufficiently so that the tooth 117 cams the collar 116 downwardly along the vertical rod 113, advancing the upper lug 112 on the brake band 111 toward the lower lug 112. This causes the brake band 111 to be contracted until it firmly grips the drum 110, effectively braking the shaft 78 and all parts rigidly connected therewith, including the gear 88, ratchet wheel 92, pinion 95, shaft 75 and feed roller 74. Thus the feed roller 74 and consequently the web W are arrested and restrained against movement when the positive drive for the feed roller 74 is interrupted in the manner above explained. The roller 131 on the arm 130 rides off the cam 132 shortly prior to the instant the roller 101 on the pawl 90 rides off the cam 100, thereby releasing the braking mechanism so that web feeding will be resumed when the pawl 90 again engages the ratchet wheel 92.

The pawl and ratchet mechanism and associated gearing disposed outwardly of the side plate 56, Figs. 4 and 5, of the web feeding and stopping unit 55 are enclosed within a housing 135 attached to this side plate. This housing is of sufficient length to also extend around the gear 88 on the printing machine A and is preferably attached in any convenient manner to the frame of the printing machine when the web handling mechanism B is assembled in operative relation thereto. A cover plate (not shown) is then attached to the housing to protect the control mechanisms enclosed therein.

After being printed upon by the printing couple 15-16, Fig. 3, the web W passes over a guide member 139 in the printing machine A and then moves horizontally over a guide plate 140 into the web severing mechanism C, Figs. 1, 2, 8 and 9. The web severing mechanism C includes side

plates 141 to which are secured angle bars 142 that abut and are secured to the frame of the printing machine A. Braces 143 extend between a tie rod 144 on the frame 29 of the printing machine A and a tie rod 145 interconnecting the side plates 141 of the mechanism C. Horizontal slots 146 are afforded in the side plates 141, these slots being transversely aligned with each other and extending the greater part of the length of these side plates.

A grate-like structure for supporting the web W after it passes over the guide plate 140 is constructed of a plurality of parallel bars 147, Figs. 8 and 9, which are individually secured to a rod 148 extending between the side plates 141. The bars 147 extend horizontally at right angles to the rod 148 and rest upon another rod 149 disposed parallel and in spaced relation to the rod 148. The ends of the rods 148 and 149 are received in the slots 146 and these rods are provided with collars 150 and clamping nuts 151 which are disposed on opposite sides of one of the side plates 141 for the purpose of securing the rods 148 and 149 in desired positions along the slots 146.

The web severing knife or cutter and associated web and sheet handling devices are supported by a base plate 154, Figs. 9 and 10, extending between the side plates 141. Threaded projections 155 on the ends of the base plate 154 are received in the slots 146 and are provided with clamping nuts 156 for adjustably securing the knife or cutter in the desired position relative to the printing machine A. The frame 157 of the web severing knife or cutter depends from the base plate 154 and is supported thereby. A flat stationary knife blade 158 is secured to the frame 157 horizontally on a level with the grate bars 147. The movable knife blade 159 is positioned for operative cooperation with the cutting edge of the stationary blade 158 and is secured to a bar 160 extending transversely between a pair of arms 161. The cutting edge of the movable blade 159 is tapered upwardly from each end thereof toward the middle of the blade in the form of an inverted V, as shown in Fig. 10. The depending end portions of the blade 159 abut the end portions of the cutting edge of the stationary blade 158 at all times, these two blades being maintained in contact with each other by springs 162, Fig. 8, extended between the arms 161 and anchors on the cutter frame 157.

The arms 161 carrying the movable knife blade 159 depend downwardly below the level of the stationary blade 158 and are connected by arms 165 to a rock shaft 166 journaled in brackets 167 included in the cutter frame 157. Springs 165' extended between the arms 165 and the cutter frame 157 tend to maintain the knife bar 160 in raised position to enable the web W to be advanced beneath the movable blade 159. The slope of the cutting edge of the blade 159 on either side of the apex thereof is such that sufficient clearance is afforded to enable the web to freely pass beneath the blade 159 when the same is in its raised position. An arm 168 secured to and depending from the rock shaft 166 is connected by a slotted link 169, Figs. 9 and 3, and a clamping member 170 to another link 171 pivotally connected to a lever 172 having a follower cooperating with a cam 173 on the shaft 85 in the printing machine A. As the cam 173 rotates it rocks the lever 172, causing the links 171 and 169, Figs. 3 and 9, to be pulled to the

left as viewed in these views, whereupon the vertically movable arms 161 are pulled downwardly by the arms 165 on the rock shaft 166 and the movable knife blade 159 descends to sever a sheet from the web W. A clamp bar 164 is connected to the knife bar 160 by bolts 163' which freely pass thru the bar 160 and are threaded into the bar 164. Coiled springs 163 surround the shanks of the bolts 163' intermediate the bars 160 and 164. A rubber strip 164' imbedded in the bar 164 engages and clamps the web W immediately in back of the knife blade 159 when the knife bar 160 descends, the springs 163 yielding as the knife blade 159 severs the web. The cam 173, Fig. 3, is so disposed on the shaft 85 that the web severing operation occurs during intervals when the web W is stationary, it being recalled that the shaft 85 also drives the parts in the web feeding and stopping unit 55 which intermittently advance and arrest the web W.

It is desirable to provide a feeding means to act on the web W as it is advanced beneath the knife blade 159, the purpose of this being to maintain the web taut and smooth. Accordingly, in the present instance, a series of feed rollers 175, Fig. 10, fixed to a shaft 176 journaled in the cutter frame 157 below the plane of the web W, cooperate with the downwardly facing or unprinted surface of the web W intermediate the grating 147 and the knife blade 159. A pulley 177, Fig. 9, on the shaft 176 is connected by a belt 178 to a pulley 179, Figs. 9 and 3, on a constantly rotating shaft 180 in the printing machine A. The belt 178 is passed about various guide pulleys 181, Fig. 9, on the frames of the printing machine A and web severing mechanism C and also around a tightening pulley 182 mounted on a clamp block 183, Figs. 8 and 9, adjustably positioned on a bar 184 which extends between the tie rod 145 and a stud 146 fastened to one of the side plates 141. The roller 182 serves to take up the slack in the belt 178, as will be explained presently. The pulley 179 on the printing machine A, through the medium of the belt 178, drives the shaft 176 carrying the rollers 175 in a clockwise direction, as viewed in Fig. 9, thereby tending to urge the web W toward the knife blade 159.

For the purpose of lightly pressing the web W against the rollers 175, discs 185 are pivotally mounted on arms 186 pivoted to a stationary shaft 187 carried by upwardly extending portions of the cutter frame 157, these discs being urged by gravity toward the feed rollers 175. The web W is guided by fingers 188 adjustably secured to a bar 189 on the frame 157 as it passes over the feed rollers 175 and thence beneath the knife blade 159. The feed rollers 175 continue to operate after the web is arrested and thereby serve to maintain the web under a slight tension for the purpose aforesaid. The discs 185, of course, do not move relative to the web W so that there is no danger of smearing any undried ink on the printed surface of the web.

As the sheets are successively severed from the web they are deposited in a suitable receptacle 190, Figs. 1 and 2, upon a delivery table 191. This table, as shown in Figs. 9 and 10, is attached to and supported by a vertically movable frame 192 having a screw-threaded connection with a vertical threaded shaft 193, Figs. 10 and 11, journaled in the cutter frame 157. The table frame 192 is also slidably connected to vertical rods 194 supported by the cutter frame 157, these rods serving to guide the table frame 192 in its vertical move-

ment. A ratchet 195 is fixed to the threaded shaft 193, Fig. 11, and a pawl 196 is arranged to cooperate with this ratchet, the pawl being connected by a link 197 to an arm 198, Figs. 9, 10 and 11, on the rock shaft 166. The pawl 196 is reciprocated in timed relation with the operation of the knife to impart a step of advancing movement to the ratchet 195 each time a sheet is severed from the web. The actuation of the ratchet by the pawl is so regulated that the threaded shaft 193 is turned sufficiently to lower the table frame 192 substantially in the amount of the thickness of a single sheet during each cutting operation, so as to maintain the top of the pile of cut sheets at the proper level to receive new sheets as they are severed from the web.

Provision has been made in the present machine for varying the lengths of the sheets printed and severed from the web. This is accomplished by varying the effective length of the adjustable cam 100, Fig. 4, to thereby regulate the amount of web which is advanced in each operation of the web feeding unit 55. In order to accurately sever the printed portion of the web intermediate the spaced impressions thereon, the cutter frame 157, Figs. 8 and 9, is adjusted longitudinally of the web by loosening the nuts 156 and moving the entire cutter frame 157 and connected parts to the desired position. The clamp 170, Fig. 3, which connects the links 169 and 171, and the clamp block 183 carrying the web tightening pulley 182 must also be loosened. When the cutter frame 157 has been moved to a position in which the cutting edges of the knife blades 158 and 159 are accurately disposed intermediate the impressions on the web W when the web is brought to rest, the nuts 156 and the clamp 170, Fig. 3, are again tightened, and the clamp block 183, Fig. 9, is tightened after it has been moved into a position to take up the slack in the belt 178. The delivery table 191 is bodily movable with the cutter frame 157, as are also the web feeding rollers 175, Fig. 10, and hence no separate adjustments of these parts are necessary.

From the foregoing description it is believed to be apparent that I have provided a web handling apparatus for use in printing machines which materially expedites the feeding and severing of web material in such machines. The invention is particularly advantageous in that it may be employed to adapt conventional printing machines, which ordinarily handle individual sheets or forms, to the handling of web material. The web feeding and stopping means is so arranged that any unwanted movement of the web is prevented and accuracy in the sizing of the sheets is insured, and various adjustments are afforded whereby the size of the sheets may readily be varied.

While I have illustrated and described a selected embodiment of my invention, it is to be understood that this is capable of variation and modification and I therefore do not wish to be limited to the precise details set forth, but desire to avail myself of such changes and alterations as fall within the purview of the following claims.

I claim:

1. In a web handling mechanism for use with a printing machine, means for supplying a web, a feed roller and an opposed pressure roller engaging said web with a continuous clamping action, a rotating member, a toothed wheel mounted coaxially with said rotating member, means interconnecting said wheel and said feed roller, a

pawl mounted on said rotatable member and normally engaging said wheel to drive said wheel and said feed roller rotatively, a stationary cam effective during a portion of each rotation of said member to disengage said pawl from said wheel, a brake effective to restrain said feed roller against movement, means for operating said brake, and a part carried by said rotatable member for actuating said brake operating means to apply said brake when said pawl is disengaged from said wheel.

2. In a web handling apparatus for use with a printing machine, web supply means, a feed roller and an opposed pressure roller between which a web from said supply means may be passed, a constantly rotating driving member, a driven member disposed in coaxial relation to said driving member and operatively connected to said feed roller for imparting rotary feeding movement thereto, means for releasably connecting said driving and driven members, means controlling said connecting means to connect said driving and driven members during a portion of a rotative cycle of the driving member and to disconnect said members during the remainder of such cycle, brake means operatively associated with said feed roller to stop said feed roller, and operating means for said brake means for applying and releasing said brake means, and including an element carried on said driving member and operable to release said brake means when said driven member is connected to said driving member and to apply said brake means when said driven member is disconnected from said driving member.

3. In a web handling mechanism for use with a printing machine, means for supplying a web, a feed roller and an opposed pressure roller for engaging a web, a rotating member, a toothed wheel mounted coaxially with said rotating member, means interconnecting said toothed wheel and said feed roller, a pawl mounted on said rotatable member and having an active position wherein it is engaged with said toothed wheel to drive said feed roller and having an inactive position wherein it is disengaged from said toothed wheel, spring means urging said pawl toward said active position, a first cam follower on said pawl, a stationary cam having a leading cam surface adapted to be engaged by said first cam follower at a predetermined point in the rotative movement of said rotating member to disengage said pawl from said toothed wheel, said cam having means affording a dwell surface of adjustable length operable upon said first cam follower to maintain said pawl out of engagement with said toothed wheel for an adjustably predetermined portion of the rotative movement of said rotating member, a brake having released and applied relationships and operable when applied to restrain said feed roller against movement, means normally operable to release said brake, means for applying said brake, including a second cam follower, and a cam mounted on said rotating member and arranged to engage said second cam follower at substantially the same time that said leading surface is engaged by said first cam follower.

4. In a printing machine adapted to operate on a web supplied thereto, a rotating printing couple having a printing medium intermittently engageable with the web to make successive impressions thereon, web supply means, web looping means controlling said web supply means and operable to form a supply loop of predetermined size in

the web, a feed roller and an opposed pressure roller for engaging the web between said looping means and said printing couple, a rotating member rotatable synchronously with said printing couple, a toothed wheel mounted coaxially with said rotating member, means interconnecting said toothed wheel and said roller, a pawl mounted on said rotatable member and having an active position wherein it is engaged with said toothed wheel to drive said feed roller and having an inactive position wherein it is disengaged from said toothed wheel, spring means urging said pawl toward said active position, a first cam follower on said pawl, a stationary cam having a leading cam surface adapted to be engaged by said first cam follower at a predetermined point in the rotative movement of said rotating mem-

ber to disengage said pawl from said toothed wheel, said cam having means affording a dwell surface of adjustable length operable upon said first cam follower to maintain said pawl out of engagement with said toothed wheel for an adjustably predetermined portion of the rotative movement of said rotating member, a normally released brake operable when applied to restrain said feed roller against movement, and means 10 for applying said brake including a second cam follower and a cam mounted on said rotating member and arranged to engage said second cam follower and apply said brake at substantially the same time that said leading cam surface of said stationary cam is engaged by said first cam follower.

CHARLES H. SAND.
